UNITED STATES PATENT OFFICE

J. ADDISON CROWELL, OF WALLKILL, NEW YORK, ASSIGNOR TO JAMES B. CROWELL & SON, OF WALLKILL, NEW YORK, A CORPORATION OF NEW YORK

BRICK MOLD

Application filed September 26, 1930. Serial No. 484,567.

My present invention relates to brick molds, and more particularly to a novel and improved brick mold particularly adapted and intended for use in the present high speed automatic brick machines.

Brick molds for this purpose have a plurality of individual molds or cavities, to enable a large number of bricks to be molded simultaneously as these molds are being passed through the automatic brick making machines.

A serious disadvantage has existed in prior molds of this type in that sand and water has collected between the end partition and the end blocks, there being a slight space left between the end block and the end partition to permit expansion and contraction of the wood of the mold under the varying conditions of moisture and dryness to which these molds are subjected. At the top of each end of present molds an iron plate is attached in such a manner as to entirely cover the end blocks and the end partitions. Thus, when passing through the sanding machines, sand works into the spaces between the end partitions and the end blocks, and when the mold is soaked, water also works into this space. This causes considerable delay, since the molds must all be drained of water before the molds can be put in operation, as otherwise the molding sand will become moist and wet and unsuitable for use.

A further disadvantage of the present type of molds resides in the fact that there being no free removal provided for the sand and water as above mentioned, the ends of the molds become distorted, and when being dumped, the bricks in the end cavities or molds will not dump, but will be held in said cavities by the distortion of the molds.

An important object of the present invention, therefore, resides in the provision of a brick mold that will dry at the ends as readily and as easily as at the center.

Another object of my invention resides in the provision of a brick mold that will not be subject to distortion at the end partitions.

A still further object of my invention resides in the construction of a mold that will

automatically free itself from sand and water at the end blocks.

A further object of the invention resides in the provision of a brick mold which will dump the bricks therefrom at the ends as well as at the center.

These features, objects and advantages, will be readily apparent to and appreciated by those skilled in the art, enabling molds constructed according to my invention to be kept in constant operation without the previous delays necessary for thorough drying, and resulting in the smooth dumping and delivery of bricks from the individual cavities of my novel mold.

In carrying out my present invention, I provide an iron plate on the top of each end block, but space this iron plate from the top of the adjacent end partition, which may or may not have an iron plate also thereon. I also space the end block from the end partition throughout their entire height, and also space the bottom of the end block from the adjacent mold bottom panel.

Thus a continuous and uninterrupted passage is provided from top to bottom of my novel mold at each end thereof. Thus when a mold constructed according to my invention is passed through the sanding machine, no sand will collect between the end partition and the end block, but will drop completely therethrough. Also, when the molds are soaked during the process of brick manufacture, the water will pass directly through the mold at the point between the end partition and the end block. Thus, when the mold is drying, the entire mold will dry evenly, and there will be no distortion of the end partition due to the presence of water and sand in the space between the end block and end partition.

I believe that a mold constructed as above briefly described is novel, and have therefore, claimed the same in this application.

The above and other objects and features of the invention, details of construction, combinations, and advantages, will be herein-after more fully pointed out, described, and claimed.

Referring to the drawings, illustrating a

preferred embodiment of the present invention,

Fig. 1 is a top plan view of a mold constructed according to my invention;

5 Fig. 2 is a bottom plan view of said mold;

Fig. 3 is a fragmentary longitudinal sectional view on the line 3—3 of Fig. 1; and

Fig. 4 is a cross sectional view on the line 4—4 of Fig. 1.

10 Referring now to the drawings, for a particular description of the invention, my present mold comprises sides 1, end blocks 2, partitions 3 and end partitions 4, together with bottom panels 5, and a bottom panel 6 under the end blocks, if desired.

15 Iron straps 7 are affixed to the top of each side by screws 8, and similar straps 9 are affixed to the bottom panels and sides. As clearly illustrated in Fig. 3, I space the end block 2 from the partition 4, and provide on top of the end block 2 a metallic plate 10, secured thereto by screws 11. Reinforcing straps 12 are also secured to the top of each partition by screws 13.

20 25 From an inspection of Fig. 3, it will be noted that the inner edge of the plate 10, the inner edge of the block 2, and the inner edge of the panel 6, constitute a continuous wall, all being spaced, as illustrated at 14, from the end partition 4, strap 12, and adjacent bottom panel 5.

30 35 When being passed through the sanding machine, sand will collect in the individual mold cavities A, but will pass completely through the passage 14, thus preventing any collection thereof in the space between the end block 2 and partition 4. Also, when subjected to wetting or soaking, water will pass directly through said passage 14, thus preventing any accumulation of surplus water or moisture which would otherwise delay the drying step after each molding operation.

40 45 The presence of the through-and-through passage 14 from top to bottom at each end of the mold will not detract from the strength and ruggedness of these molds, nor from their ability to withstand the blows, shocks and hammerings to which such molds are subjected during the process of brick manufacture.

50 55 The presence of the vents 15 in each individual mold cavity will provide for the ejection of superfluous sand and water, and will also permit easy ejection or dumping of the bricks from the individual mold cavities A.

60 65 While I have necessarily described my present invention somewhat in detail, it will be appreciated that I may vary the size, shape, and arrangement of parts, within reasonably wide limits without departing from the spirit of the invention.

70 75 My invention is further described and defined in the form of claims as follows:

80 85 85 1. A brick mold of the kind described hav-

ing a passage completely through the mold from top to bottom thereof between each end block and its adjacent end partition.

2. A brick mold comprising sides, bottom panels, partitions and end blocks, a metallic plate affixed to the top of each end block, and a panel under each end block, the inner sides of said metallic plate, said end block and said end block panel constituting a continuous flush wall spaced from the adjacent end partition and adjacent bottom panel.

75 In testimony whereof, I have signed my name to this specification.

J. ADDISON CROWELL.
